CLAIM

The ornamental design of a sear for a bowstring release, as shown and described.

DESCRIPTION

FIG. 1 is a perspective view of an embodiment of a sear for a bowstring release;

FIG. 2 is a side view of the sear of FIG. 1;

FIG. 3 is a side view of the sear of FIG. 1 opposite the side view illustrated in FIG. 2;

FIG. 4 is a front view of the sear of FIG. 1;

FIG. 5 is a rear view of the sear of FIG. 1;

FIG. 6 is a top view of the sear of FIG. 1;

FIG. 7 is a bottom view of the sear of FIG. 1;

FIG. 8 is a perspective view of another embodiment of a sear for a bowstring release;

FIG. 9 is a side view of the sear of FIG. 8;

FIG. 10 is a side view of the sear of FIG. 8 opposite the side view illustrated in FIG. 9;

FIG. 11 is a front view of the sear of FIG. 8;

FIG. 12 is a rear view of the sear of FIG. 8;

FIG. 13 is a top view of the sear of FIG. 8; and,

FIG. 14 is a bottom view of the sear of FIG. 8.
